US0D1051535S

(12) **United States Design Patent** (10) **Patent No.:** **US D1,051,535 S**
(45) **Date of Patent:** **** Nov. 12, 2024**

(54) **AIR BLOW**

(71) Applicants: **Junhuan Liu**, Guangdong (CN); **Jun Yang**, Guangdong (CN); **Shixian Ye**, Guangdong (CN)

(72) Inventors: **Junhuan Liu**, Guangdong (CN); **Jun Yang**, Guangdong (CN); **Shixian Ye**, Guangdong (CN)

(73) Assignee: **Shenzhen Anymore Technology Limited**, Linghua District (CN)

(**) Term: **15 Years**

(21) Appl. No.: **29/896,427**

(22) Filed: **Jul. 3, 2023**

(51) LOC (14) Cl. **07-05**

(52) U.S. Cl.

USPC **D32/35**

(58) **Field of Classification Search**

USPC D32/35, 40

CPC A47L 7/0052; A47L 7/0071; A47L 7/0095

See application file for complete search history.

(57) **CLAIM**

The ornamental design for an air blow, as shown and described.

DESCRIPTION

FIG. 1 is a front elevational view thereof;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of air blow my new design; and,

FIG. 8 is a perspective view of air blow my new design.

1 Claim, 8 Drawing Sheets
